UNITED STATES PATENT OFFICE

2,431,610

MAST

Harold Cohen, Elizabeth, N. J.

Application April 10, 1945, Serial No. 537,499

3 Claims. (CL 189—25)

1

This invention relates to a structure in the form of a mast, pole or tower.

An object of the present invention is the provision of a structure of the indicated character embodying improvements in construction whereby the structure will have the necessary strength and rigidity in order that it may be raised or erected from a horizontal to a vertical position.

A further object is the provision of a structure of the character mentioned which is not only strong and rigid, but which is light in weight and offers a minimum resistance to the wind considering the size of the structure.

The invention also resides in the simplicity of the construction of a mast or tower, the economy with which it may be produced and the general benefits derived therefrom.

The nature of the invention and its distinguishing features and advantages will appear when the following specification is read in conjunction with the accompanying drawing, in which—

Fig. 1 is a fragmentary side elevational view of a mast or tower embodying the features of the invention, portions being shown in section.

Fig. 2 is an enlarged horizontal sectional view taken on the line 2—2 of Fig. 1.

Figs. 3, 4 and 5 are detail vertical sectional views taken on the respective lines 3—3, 4—4 and 5—5.

Referring now to Fig. 1 of the drawing, it will be apparent that the mast or tower, generally stated, consists of similar sections 10 joined in end-to-end relation. Each of the sections 10 consists of leg members or uprights 11, spanners or transverse members 12 secured to said members 11 near the ends, respectively, of the section, and spanners or cross-ties 13 secured to said members 11 intermediate the ends, to retain said members 11 in spaced relation to each other.

The leg members or uprights 11 may be of wood or metal, and are preferably in the form of metal tubes of suitable length, as shown in the present instance.

The spanners 12 are circular or annular, or in other words, the spanners 12 consist of rings of similar shape in cross-section, and of equal diameter in the present case. Each spanner 12 is of hollow construction, and is round in cross-section. The spanner has aligned holes 14 arranged in pairs, and the pairs are spaced equally with respect to each other. There are twelve pairs of holes 14 in each spanner 12 in the present instance. Obviously, more or less pairs may be provided according to the number of leg or up-

2

right members 11 desired for strength and rigidity. Cross braces 15 are welded at their ends to the spanner 12, said braces 15 are disposed diametrically with respect to spanner and crosswise with respect to each other. Each spanner 12 also has connected therewith a plurality of U-bolts 16. Suitable washers 17 are arranged on the ends of each bolt 16 between the spanner and the nuts 18.

10 The intermediate spanners 13 are similar to the spanners 12, except that the spanners 13 do not carry any U-bolts. Features of the spanners 13 similar to those of spanners 12 are given corresponding reference numerals.

15 The lower end of each leg member or upright 11 has a tubular splice 19 welded thereto. The splice surrounds said member 11 for one-half the length of the splice leaving the other half to provide a socket for the upper end of a second leg member 11, so that the leg members may be joined in pairs.

20 The parts of a section or unit 10 are assembled as follows. The required number of leg members or uprights 11 are severally extended through pairs of the holes 14 in a plurality of the spanners 13, which are disposed intermediate the ends of the members 11, and welded thereto in spaced relation. The members 11 are also extended in the holes 14 of two spanners 12 which 25 are disposed near the opposite ends, respectively, of the section or unit 10 providing an upper and a lower spanner 12 for each section 10. The spanners are welded to the members 11, the lower spanner 12 of the section 10 abutting the splices 19. Braces 20 in the form of rods or 30 lengths of cable, as shown in the present instance, are connected with the U bolts 16 on the spanners 12 so as to be disposed diagonally. The nuts 18 may be adjusted to draw the U-bolts to 35 tighten the braces 20.

40 The completed sections or units 10 are rigidly joined to each other end-to-end or in superimposed relation and the members 11 of the sections 10 in longitudinal alinement with each other as 45 follows. The upper ends of the members 11 of one section 10 are projected into the splices 19 of a second section or unit. Suitable fastening elements, such as the bolts 21, are employed in conjunction with the opposing spanners 12 of two sections 10 to securely draw them toward each other. The bolts 21 extend loosely through said spanners 12 which have holes therein for that purpose. Each bolt 21 has an adjustable nut 22 and washers 23 on the bolt conform to and bear 50 on the circular surface of the related spanner 12. 55

Thus, the sections 10 are rigidly joined, although capable of being separated should the occasion arise to dismantle the structure.

The sections or units 10 may be readily assembled on the ground leaving the completed mast or tower prone or horizontal. The mast or tower is strong and of unusual rigidity. This enables it to be raised from a horizontal position to a vertical position of use. The mast or tower constructed in the manner described and illustrated offers a minimum of resistance to the wind and a maximum of stability in use.

The mast or tower may be constructed without the diagonal braces 20, if desired, especially if it is not built to any comparatively great height.

It is to be understood that in accordance with the invention, a mast or tower may be triangular, square or any other shape in horizontal cross-section. Therefore, the spanners may be triangular, square or even straight. Also, the mast or tower in general design may be tapered or pyramidal. However, a construction as shown may be fabricated at less cost than one which is tapered.

I claim:

1. In a tower or mast, pairs of leg members, 25 cross-tie elements, the leg members of each pair extending through aligned holes in said elements respectively, in end-to-end abutting relation to each other and rigidly secured to said elements, a splice member telescoping the end portions of 30 each pair of leg members between said elements, said splice member being in non-threaded engagement with said leg members and abutting

said cross-tie elements, and securing means to secure said elements, leg members and splice members in rigidly assembled relationship.

2. In a tower mast, as set forth in claim 1, 5 wherein said securing means extends through said cross-tie elements.

3. In a tower or mast, pairs of leg members, 10 annular one-piece spanners, the leg members of each pair extending through aligned holes in said spanners respectively, and rigidly secured thereto, a splice member telescoping the end portions of each pair of leg members between said spanners, 15 said splice member being in non-threaded engagement with said leg members and abutting said spanners, and securing means extending through said spanners to secure said spanners, leg members and splice members in rigidly assembled relationship.

HAROLD COHEN.
